UNITED STATES PATENT OFFICE

CHARLES E. KNEPPER, OF INDIANAPOLIS, INDIANA, ASSIGNOR TO NEWSPAPER BOYS OF AMERICA, INCORPORATED, OF INDIANAPOLIS, INDIANA, A CORPORATION

DESIGN FOR A MEDAL

Application filed June 2, 1932. Serial No. 43,960. Term of patent 14 years.

To all whom it may concern:

Be it known that I, CHARLES E. KNEPPER, a citizen of the United States, residing at Indianapolis, in the county of Marion and state of Indiana, have invented a new, original, and ornamental Design for Medal, of which the following is a specification, reference being had to the accompanying drawing, forming part thereof.

The figure is a perspective view of a substantially flat medal, showing my new design.

I claim:

The ornamental design for a medal, as shown and described.

CHARLES E. KNEPPER.
